UNITED STATES PATENT OFFICE

HERBERT R. JORDAL, OF MINNEAPOLIS, MINNESOTA, ASSIGNOR OF TWO-FIFTHS TO
PALMER H. HJELLE, OF MINNEAPOLIS, MINNESOTA

TURNTABLE

Application filed July 2, 1931. Serial No. 548,360.

This invention relates to turntables and relates particularly to turntables adapted to be used in connection with automobile trucks. In road building and other building operations, trucks carrying building materials must often be used on narrow roadways where room is not provided for turning the trucks under their own power. Portable turntables are now extensively used for turning the trucks, but the turntables now on the market have not been of rugged enough construction to stand up under the continued hard usage to which they are put.

It is the object of this invention to provide a novel and improved turntable including a pair of spaced runways adapted to receive the wheels of a truck and both tiltable about a horizontal axis and rotatable about a vertical axis, which turntable shall be of extremely strong and rugged construction to stand up under continued usage and will yet be of simple construction.

To this end, the invention consists in the novel parts and novel combinations of parts, hereinafter defined in the claims and described in the following specification, made in connection with the accompanying drawings, wherein like reference characters refer to the same or similar parts throughout the various views, and in which,

Fig. 1 is a plan view of a turntable embodying the present invention;

Fig. 2 is a view in side elevation of the same illustrating in full lines the position that the runways and parts connected thereto will assume when in unloaded horizontal position, and illustrating in dotted lines the position that the runways and parts connected thereto will assume when tipped toward the ground at one end of the turntable;

Fig. 3 is a vertical longitudinal section taken on the line 3—3 of Fig. 1, as indicated by the arrows, and illustrating the runways and parts connected thereto in the position they will assume when in horizontal unloaded condition; and

Fig. 4 is a transverse vertical section taken on the line 4—4 of Fig. 2, as indicated by the arrows.

Referring to the drawings, and in accord-

ance with the present invention, there is provided an inverted turtle-back 5 of octagonal shape in plan view, as shown in Fig. 1 and preferably of greater length than width. The edges of this turtle-back are curved upwardly from the flat central portion and side runners 6 and a central runner 7 are secured to the bottom of the turtle-back to extend longitudinally of the same. The central runner 7 is projected at its end portions beyond the two ends of the turtle-back and the end portions are reversely bent inwardly and secured to the upper surface of the turtle-back to form eyes to which cables may be attached for dragging the turntable along the ground. The runners 6 and 7 will, of course, permit the turtle-back to readily slide along the ground and will give direction to the movement of the turtle-back. Secured to the turtle-back 5 and projecting upwardly therefrom is a block 8 having a circular top surface provided with a circular groove 8a forming a lower raceway for a plurality of ball bearings 9. A platform 10 of rectangular shape is located above the block 8 and is held to the block by means of a king bolt 11 running centrally through the block and platform. The lower surface of the platform 10 is provided with a circular groove 10a which forms an upper raceway for the ball bearings 9. Projecting upwardly from the platform 10 and formed integral therewith or secured thereto are a pair of spaced risers 12 having vertical slots 12a therein. The two risers 12 are located in parallel spaced relation adjacent the central portions of the platform 10 and extend longitudinally thereof to form bearings for a cross shaft to be later described. Straps 13 run across the upper open ends of the slots 12a and may be suitably secured to the risers 12 as by means of screws 14.

A pair of spaced parallel runways 15 of channel-shape in vertical cross section are provided and each runway may be suitably constructed from a pair of spaced parallel angle bars 15a interconnected by long strips of sheet metal 15b secured to the oppositely projecting horizontal flanges of the angle bars. Preferably the vertical flanges of the angle bars 15a are beveled at their ends as

best shown in Fig. 2, and the ends of the strips 15b of sheet metal are clinched over the ends of the horizontal flanges of the angle bars. The two runways 15 are interconnected by a pair of heavy central cross bars 16 which extend between and across the two runways 15 below the same and are secured to the runways. The two central cross bars 16 are spaced from each other a distance approximating the usual length of wheel base of a truck and are respectively spaced equal distances from the centers of the runways 15 taken longitudinally thereof. End cross bars 17 are also provided which extend transversely between and across the two runways 15 adjacent the ends of the same and below the same, these end cross bars are also secured to the runways. To give the runways great strength, each runway is provided with a pair of truss bars 18 which extend longitudinally of the runways below the horizontal flanges of the angle bars 15a and these truss bars are connected to the cross bars 16 and 17 below the same. To make a more rigid construction and to transmit the load from the end cross bars 17 to the central cross bars 16, pairs of diagonal brace bars 19 are used, which are respectively connected at their ends to the end cross bars 17 and the central cross bars 16 and the diagonal bars 19 of each pair cross each other between the end cross bar 17 to which they are connected and the central cross bar 16 to which they are connected. Four heavy transversely spaced longitudinal bars 20 extend between and are secured to the two central cross bars 16 above the same and two of these bars will be disposed in abutment with the respective inner angle bars 15a of the runways 15, and two of the longitudinal bars 20 will be inwardly disposed from the outer bars 20. The four longitudinal bars 20 overlie the platform 10 and extend longitudinally thereof. A cross shaft 21 is mounted in the four longitudinal bars 20 to extend transversely between the two runways in the center line of the runways taken longitudinally thereof. A roller 22 is journaled on the shaft 21 between the two central longitudinal bars 20 and this roller fits within the two notches 12a of the risers 12. It will be noted that the two risers 12 abut the inner sides of the two central longitudinal bars 20. Caps 23 extending longitudinally relative to the runways 15 are journaled on the shaft 21 respectively between inner and outer longitudinal bars 20 and these caps have recesses formed in their lower surfaces. Heavy coiled springs 24 fitting within circular recesses cut in the upper surface of the platform 10, bear at their lower ends against the platform 10 and at their upper ends these springs 24 fit within the recessed portions of the caps 23 and bear against the caps. It will be noted that a spring 24 is located adjacent each end of

each cap 23. Additional springs may, of course, be provided if desired to react between the cap 23 and the platform 10.

In locating the turntable preparatory to use, a cable may be attached to one of the eyes formed at one end of the central runner 11 secured to the turtle-back 5 and the turntable may be dragged along the ground to the proper position. The king bolt 11 will hold the platform 10 in place above the block 8, while the straps 13 will prevent the runways 15 and the structure directly connected thereto from moving out of position above the platform 10, as the turntable is moved over the ground. In using the turntable for road building, the turntable will be located on the roadway that is being built rearward from the immediate section upon which work is being done. As a gravel truck or other loaded truck approaches the turntable, a workman will tilt the runways 15 to the position illustrated in Fig. 2 in dotted lines, by raising the left ends of the runway. In this position, the four longitudinal bars 20 will engage one end of the platform 10 as a fulcrum, while the right ends of the runways may be engaged with the ground. The truck driver will run his loaded truck onto the two runways 15 slowly and as the center of mass of the truck is carried past the right hand end of the platform 10, the two runways 15 will tip to horizontal position, so that the four longitudinal bars 20 rest directly on the platform 10. The springs 24 acting between the caps 23 and the platform 10, serve to cushion the movement of the longitudinal bars 20 as they are carried downwardly onto the platform 10. Longitudinal sliding movement of the two runways 15 relative to the platform 10 is prevented by contact of the roller 22 with the vertical surfaces of the risers 12 adjacent the grooves 12a. As the runways 15 are carried to horizontal position, the truck will be moved forwardly on the runways until the center of mass of the truck is disposed approximately directly over the cross shaft 21. In this position, the front and rear axles of the truck will be disposed approximately over the inner cross bars 16. The weight of the truck will then be carried from the runways 15 onto the central cross bars 16 and thence from the cross bars to the longitudinal bars 20 which bear directly on the platform 10. Part of the weight of the load will be taken from the runways 15 by the end cross bars 17 and transmitted through the diagonal bars 19 to the inner cross bars 16 and thence to the longitudinal bars 20 and onto the platform 10. The four longitudinal bars 20 extend entirely across the platform 10 and distribute the load to all portions of the platform. An undue weight will, therefore, not be transmitted to any portion of the platform or to any portion of any bar that is used. The weight of the

load will be transmitted from the platform thereto in upwardly raised position from 10 to the block 8 and thence from the block to the platform 10 when no load is placed on the turtle-back 5 and the ground. No sliding movement of the runways 15 transversely of the platform can take place, both due to the abutment between the risers 12 and the central longitudinal bars 20 and also due to the abutment of the ends of the cross shaft 21 with the inner angle bars 15a of the runways. It is thus clear that shifting movement of the runways either longitudinally or transversely relative to the platform 10 is impossible. After the truck is centrally located on the runways, a workman may grasp one of the runways 15 and readily rotate the runways and platform 10 relative to the block 8 through 180°, thereby turning the truck to face in an opposite direction than formerly. The platform 10 will ride easily on the ball bearings 9 mounted on the block 8 and the truck together with the runways and platform can be very easily swung on the block 8. It will be noted that the runways 15 and all parts connected thereto which rotate therewith, have sufficient clearance from the ground when the longitudinal bars 20 are resting on the platform 10, so that even though the ground is not perfectly level, free rotation of the runways is possible. After the truck has been faced in an opposite direction, the truck may be backed off the runways 15, which will cause the runways to again tilt so that the longitudinal bars 20 strike one end of the platform 10 as a fulcrum and the runways strike the ground. The truck may then be backed up to the point where the load is to be delivered, and the load dumped whereupon the truck may be driven in a forward direction around the turntable away from the point where the construction work is being done. It is, of course, possible to again run the truck over the turntable on its return trip from the point where the load is dumped, inasmuch as the truck may run on to the runways 15 at either end thereof and may run off the runways 15 at either end thereof.

Attention is particularly called to the strong rugged construction of the present turntable and also to the fact that no sliding movement of the runways can take place relative to the platform 10. By supporting the load on the platform 10 from the longitudinal bars 20, an extremely stable construction is provided and there is no tendency for any one part to break due to excessive pressure applied thereto. The truss bars 18 together with the cross bars 16 and 17 bind all parts of the runways together, so that as a truck runs onto any part of the two runways, a portion of the weight of the truck will be transmitted to all other parts of the runways. The springs 24 are, of course, strong enough to maintain the two runways 15 together with the parts fixed

thereto in upwardly raised position from the platform 10 when no load is placed on the runways. Free movement for the cross shaft 21 upwardly and downwardly in a vertical plane is possible by provision of the slots 12a in the risers 12. It will, of course, be understood that various changes may be made in the form, details, arrangement and proportions of the various parts without departing from the scope of the present invention.

What is claimed is:

1. A turntable having in combination, a base, a platform mounted on said base for rotation about a vertical axis, a pair of spaced parallel runways, cross bars extending between and below said runways and to which said runways are secured, a plurality of longitudinal bars extending generally parallel to said runways and projecting entirely across said platform and secured to said cross bars, and means for connecting said longitudinal bars to said platform to permit vertical movement of said longitudinal bars relative to said platform but preventing longitudinal sliding movement of said longitudinal bars relative to said platform, said platform having end portions forming fulcrums against which said longitudinal bars are adapted to bear for tilting movement, said longitudinal bars acting to transmit the weight carried by said runways to said platform.
2. A turntable having in combination, a base, a platform mounted on said base for rotation about a vertical axis, a pair of spaced parallel runways, means interconnecting said runways and having portions extending over said platform, a cross shaft supported by said means over said platform and spaced parallel risers projecting upwardly from said platform and having vertical slots receiving said shaft, said platform having end portions forming fulcrums against which said portions of said means are adapted to bear for tilting movement, said shaft and said risers acting to prevent relative sliding movement between said runways and said platform in a direction longitudinally of said runways.
3. The structure defined in claim 2, cap members mounted on said shaft and springs disposed between said cap members and said platform.
4. A turntable having in combination, a base, a platform mounted on said base for rotation about a vertical axis, a pair of spaced parallel runways, cross bars extending between and below said runways and to which said runways are secured, a plurality of longitudinal bars extending generally parallel to said runways and running across said platform and secured to said cross bars, a cross shaft carried by said longitudinal bars and risers secured to and projecting upward-

ly from said platform, said risers having vertically extending slots within which said cross shaft fits to prevent sliding movement of said runways longitudinally of said platform, said platform having end portions forming fulcrums against which said longitudinal bars are adapted to bear for tilting movement, said longitudinal bars acting to transmit the weight carried by said runways to said base.

5. The structure defined in claim 4, said risers bearing against certain of said longitudinal bars to prevent sliding movement of said runways transversely of said platform.

15 6. The structure defined in claim 4, cap members pivoted on said cross shaft and springs disposed between said cap members and said platform and normally holding said longitudinal bars in spaced relation above 20 said platform when said runways are unloaded and acting to cushion the movement between said longitudinal bars and said platform.

7. A turntable having in combination, a 25 base, a platform mounted on said base for rotation about a vertical axis, a pair of spaced parallel runways, a plurality of cross bars extending between and below said runways and to which said runways are secured, a pair of truss members for each runway extending respectively adjacent the two sides of the runway from one end of the same to the other below said cross bars and secured to said cross bars, means extending between and secured to central cross bars and projecting across said platform to transmit the load from said runways to said platform, said platform having a pair of opposite ends forming fulcrums for tilting movement of said runways relative to said platform and means connecting said first mentioned means to said platform for vertical movement of said first mentioned means relative to said platform.

8. A turntable having in combination, a 45 base, a platform supported on said base for rotation about a vertical axis, a pair of spaced parallel runways adapted to receive the wheels of a vehicle, a pair of central cross bars extending between and secured to said runways beneath the same, one of said cross bars being disposed at either side of the lateral center line of said runways, a pair of end cross bars extending respectively between and secured to said runways below the same 55 adjacent their ends, pairs of diagonally disposed brace bars crossing each other, one pair of which are secured to and extend between one of said end cross bars and one of said central cross bars and the other pair 60 of which are secured to and extend between the other end cross bar and the remaining central cross bar, longitudinal bars secured to and extending between said central cross bars and projecting over said platform, and means for connecting said longitudinal bars

to said platform to permit vertical movement of said runways relative to said platform without permitting longitudinal shifting movement of said runways relative to said platform.

9. The structure defined in claim 4, and resilient cushioning means interposed between said platform and said shaft.

10. A turntable comprising, a turtle-back adapted to be slid over the roadway, runners carried on the lower surface of said turtle-back, an upstanding block secured to said turtle-back, a platform pivotally mounted on said block for rotation about a vertical axis, a pair of spaced parallel runways of channel-shape in vertical cross section, a pair of central cross bars extending below said runways and interconnecting the same, a pair of end cross bars extending below said runways and interconnecting the same, diagonal brace bars interconnecting the respective end cross bars to the central cross bars adjacent thereto, longitudinal bars interconnecting said central cross bars and projecting across said platform, a cross shaft carried by said longitudinal bars, vertically slotted risers projecting upwardly from said platform, a roller journaled on said cross shaft and fitting within the slots of said bearing blocks, longitudinally extending caps journaled on said cross shaft and springs at each end of said caps bearing against said platform and also bearing against said caps, said platform having a pair of opposing end portions forming fulcrums for supporting said longitudinal bars for tilting movement thereon, said springs acting to normally hold said longitudinal bars above said platform when said runways are unloaded, and also acting as cushions between said shaft and said platform.

11. The structure defined in claim 4, and trusses for each runway extending below said cross bars from adjacent one end of the runway to adjacent the other end of the same and secured to said cross bars.

In testimony whereof I affix my signature.
HERBERT R. JORDAL.
